(57) **CLAIM**

The ornamental design for a battery charging box as shown and described.

DESCRIPTION

FIG. 1 is a front, left and top perspective view of a battery charging box showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view of another state of the battery charging box thereof.

The broken lines are included for the purposes of illustrating portions of the battery charging box that form no part of the claimed design.

1 Claim, 9 Drawing Sheets
